(74) Attorney, Agent, or Firm — Clause Eight IPS;
Michael Catania(57) **CLAIM**

The ornamental design for an antenna, as shown and described.

DESCRIPTION

FIG. 1 is a top plan view of an antenna with a base in broken lines;

FIG. 2 is a front elevation view thereof;

FIG. 3 is a bottom plan view thereof;

FIG. 4 is a top perspective view thereof;

FIG. 5 is a top plan view thereof, with the unclaimed environment removed; and,

FIG. 6 is a front elevation view thereof, with the unclaimed environment removed.

The broken line in the figure drawings represents unclaimed environment only and forms no part of the claimed design.
